UNITED STATES PATENT OFFICE.

JOHN J. ARMSTRONG, OF PITTSBURG, PENNSYLVANIA.

HOSE-BRIDGE.

995,940.

Specification of Letters Patent. Patented June 20, 1911.

Application filed September 23, 1910. Serial No. 583,409.

To all whom it may concern:

Be it known that I, JOHN J. ARMSTRONG, a citizen of the United States of America, residing at Pittsburg, in the county of Allegheny and State of Pennsylvania, have invented certain new and useful Improvements in Hose-Bridges, of which the following is a specification, reference being had therein to the accompanying drawing.

10 This invention relates to hose bridges, and has for its object to provide a device of such class for bridging a line of hose in an elevated manner, particularly above a car track in case of fire.

15 Further objects of the invention are to provide a hose bridge, which is simple in its construction and arrangement, strong, durable, efficient in its use, conveniently set up to support a hose in an elevated position, and 20 inexpensive to manufacture.

With the foregoing and other objects in view, the invention consists of the novel construction, combination and arrangement of parts, as hereinafter more specifically described and illustrated in the accompanying drawing, wherein is shown the preferred embodiment of the invention, but it is to be understood that changes, variations, and 25 modifications can be resorted to, which come 30 within the scope of the claim hereunto appended.

In describing the invention in detail, reference is had to the accompanying drawings, wherein like reference characters denote corresponding parts throughout the several views, and in which:

Figure 1 is a side elevation of a hose bridge, in accordance with this invention, showing the adaptation thereof for supporting a line of hose above a car track. Fig. 2 is a perspective view of the upper portion of one of the outer supporting members of the bridge. Fig. 3 is a sectional detail of the upper portion of one of the outer supporting members of the bridge. Fig. 4 is an elevation of the intermediate supporting member of the bridge, and Fig. 5 is a sectional elevation of a modified form of intermediate supporting member of the bridge.

45 Referring to the drawings in detail, 1 and 2 denote a pair of tracks over which a line of hose 3 is supported at such an elevation, by a bridge in accordance with this invention, as to enable the passage of cars over 55 the tracks.

A hose bridge in accordance with this in-

vention comprises a pair of outer supporting members and an intermediate supporting member. Each outer supporting member consists of a head 4 provided with a plurality of pairs of apertured lugs 5, which are equally spaced, and as shown, each head is provided with three pairs of lugs. Detachably connected to the lugs of each pair by the removable pin 6 is a supporting leg 7, 65 which is adapted to maintain the head 4 in an elevated position.

The reference character 8 denotes a yoke having a shank 9 fixedly secured by the hold-fast device 10 to the head 4 centrally thereof. The inner face of each of the arms of the yoke is formed with a recess 11, in which are mounted a pair of blocks 12 having journaled therein a bearing roller 13, upon which is mounted the line of hose 3. The intermediate section consists of a head 14 provided with two oppositely disposed pairs of lugs, and in each pair of lugs 15 the upper end of the supporting leg 16 is detachably secured by a removable pin 17. The supporting legs 16 of the intermediate member are positioned centrally between the pair of tracks 1 and 2, as clearly shown in Fig. 1, and extend in opposite directions with respect to each other, so that said legs 16 will 85 not interfere with the cars, as they travel on the track. The intermediate section is fixed to the outer sections through the medium of the tie bars 18, 19, which have angle shaped ends 20 detachably engaging in openings formed in the head 4 of the outer members or sections and the head 14 of the intermediate member or section. The tie bars 18, 19, maintain the supporting members in an upright position.

95 The modified form of intermediate member shown in Fig. 5 is provided with a clamp 21 for retaining the hose upon the roller 22, whereby the intermediate supporting member will be prevented from falling.

100 The roller bearings 13 allow for the shifting of the hose in case they move longitudinally, due to the action of the engine or the pressure of the water, as it travels through the hose.

105 What I claim is:

A hose bridge comprising a pair of outer supporting members and an intermediate supporting member, each of said members being provided with a head, a pair of legs 110 supporting the head of the intermediate member, a series of legs supporting the heads

of each of the outer members, each of said outer members further comprising a vertically-disposed yoke having a relatively long shank depending centrally therefrom and 5 formed with a reduced end extending through the head of said member, means engaging the reduced end for securing the yoke to the head, each of said yokes having the inner face of each of its arms cut-away 10 to provide a recess, a vertically-disposed removable bearing mounted in each of said recesses, a bearing roller having reduced ends journaled in said bearings and posi-

tioned above the bottom of the yoke, and means for pivotally connecting the legs to 15 the head, and tie members having angle-shaped ends depending in the heads for supporting and connecting the supporting members together.

In testimony whereof I affix my signature 20 in the presence of two witnesses.

JOHN J. ARMSTRONG.
